UNITED STATES PATENT OFFICE.

JAMES E. WHITE, OF MANSFIELD, MASSACHUSETTS.

WATER-HEATING ATTACHMENT FOR HOT-AIR FURNACES.

SPECIFICATION forming part of Letters Patent No. 498,946, dated June 6, 1893.

Application filed March 3, 1893. Serial No. 464,564. (No model.)

To all whom it may concern:

Be it known that I, JAMES E. WHITE, a citizen of the United States, residing at Mansfield, in the county of Bristol and Commonwealth of

5 Massachusetts, have invented a new and useful Improvement in Water-Heating Attachments for Hot-Air Furnaces, of which the following is a specification, reference being had to the accompanying drawings, which form a part hereof.

My invention relates to a hot-air furnace of the kind commonly known as the Chilson cone furnace, and the object of my invention is to combine with such a furnace a water-heating attachment by which heat may be distributed to portions of the building which are not easily heated by the hot air alone, but without detracting from the hot-air heating capacity of the furnace.

20 My invention consists in a hot-air furnace having a fire-pot with a series of pockets in the upper part of its inner periphery in combination with an annular water-chamber somewhat oval in vertical cross-section, tapering 25 toward the top and toward the bottom, and having lugs by which the water-chamber is supported by the rim of the fire-pot out of contact with the fuel, and a series of connecting pipes leading from the annular water-30 chamber to a second water-chamber whence the hot water is conducted to the radiators, the pockets in the rim of the fire-pot allowing free passage of the heated gases so that the 35 annular water-chamber and its connecting pipes are exposed to direct heat on all sides.

In the drawings, Figure 1 is a longitudinal section of a Chilson cone furnace with my water-heating device attached. Fig. 2 is a cross-section. Fig. 3 is a top view of the fire-40 pot. Fig. 4 is a top view of the annular water-chamber detached, and Fig. 5 is a bottom view of the same.

45 In the furnace itself which is too well known to require detailed description, A is the casing and B are the cone sections which carry the products of combustion from the combustion chamber B' to the annular pipe C whence they pass off through pipe C' to the chimney. The heated air in the space D' between the 50 furnace and casing passes to the registers (not shown in the drawings) through pipes leading from the furnace at D.

E represents the feed-door, F the fire-pot and F' the ash-pit. The fire-pot has a series of concave recesses or pockets f around its 55 upper edge as shown in Figs. 1 and 3.

The annular water-chamber G is a hollow cast-iron ring made somewhat oval in cross-section, tapering toward the top and toward the bottom, except where it is cut away at g 60 in front of the feed-door to allow passage of the fuel. This water-ring G is of as large exterior diameter as can go inside the fire-pot in order to secure as much surface exposure as possible. It has flanges or lugs g² which 65 project onto the rim f' of the fire-pot and support the water-ring above and out of contact with the fuel unless the fire-pot be filled up higher than is usual or desirable, the lower tapered portion of the water-ring projecting 70 into the upper part of the fire-pot and the upper tapered portion extending up into the combustion chamber. I desire to get the greatest possible surface exposure of the water-ring to the heated gases with the least 75 possible obstruction, and also to prevent as far as possible the collection of ashes which will gather on a flat surface, and by reason of their non-conducting character impair the efficiency of the water-ring. For these reasons 80 I make my water ring somewhat tapering in cross-section both toward the top and toward the bottom except where cut away at g as already described. On account of the cutting away at g the section of the ring from which the cutting is taken is extended downward a 85 little lower than the rest of the rings, in order to secure sufficient sectional area for good circulation.

A series of connecting pipes l, preferably 90 equal in number to the pockets in the rim of the fire-pot are connected with the water-ring through the bosses g' and lead thence to an upper chamber L whence the hot water is conducted through the flow-pipes M and N to radiators (not shown in the drawings) and back through the return pipes R. The relative size 95 of the several pipes should be such as to secure proper circulation and is well known in the art. The pipes S lead to additional radiators. 100

When the water-ring is placed on its seat there will be a series of open passages from the fire-pot up through the pockets f so that

not only will the inner periphery of the water-ring and the pipes *l* be directly exposed to the heated gases, but also, although the water-ring is as large in diameter as will go into the fire-pot, yet the tapered form of the ring exposes that portion of the outer periphery which is within the fire-pot directly to the heated gases, and the series of pockets *f* allow free passage of the gases up around the outer, upper portion of the periphery, and thereby the same amount of fire will heat the water much more quickly and to a higher temperature than if the inner periphery of the ring alone were directly exposed to the gases.

15 I prefer to make the water-ring with a series of concave recesses *h* in the lower tapered portion of its outer periphery, which come opposite the pockets of the fire-pot, thus increasing the size of the passages.

20 What I claim as my invention is—

1. A hot-air furnace with hot-air pipes leading to registers and having a fire-pot with a series of pockets in the upper part of its inner periphery, in combination with an annular water-chamber as large in diameter as will go inside the fire-pot, and having projections which rest on the rim of the fire-pot and support the water-ring, a series of connecting pipes leading from the annular water-chamber to an upper chamber, a flow-pipe leading thence to a radiator and a return pipe from the radiator to the annular water-chamber, substantially as described.

2. A hot-air furnace with hot-air pipes leading to registers and having a fire-pot with a series of pockets in the upper part of its in-

ner periphery, in combination with an annular water-chamber as large in diameter as will go inside the fire-pot, tapered in cross-section toward the top and toward the bottom, and having projections which rest on the rim of the fire-pot and support the annular water-chamber out of contact with the fuel, a series of connecting pipes leading from the annular water-chamber to an upper chamber, a pipe 4 leading thence to a radiator and a return pipe from the radiator to the annular chamber, substantially as described.

3. A hot-air furnace with hot-air pipes leading to registers and having a fire-pot with a series of pockets in the upper part of its inner periphery, in combination with an annular water-chamber as large in diameter as will go inside the fire-pot, tapered in cross-section toward the top and toward the bottom, and having projections which rest on the rim of the fire-pot and support the annular water-chamber partly within the combustion chamber and partly within the fire pot, out of contact with the fuel, a series of recesses in the lower portion of the outer periphery opposite the pockets in the fire-pot, a series of connecting pipes leading from the annular water-chamber to an upper chamber, a flow pipe leading thence to a radiator, and a return pipe from the radiator to the annular chamber, substantially as described.

JAMES E. WHITE.
